Patented Nov. 15, 1927.

1,649,590

UNITED STATES PATENT OFFICE.

FREDERICK HENKE, OF PHILADELPHIA, PENNSYLVANIA, ASSIGNOR TO FOX AUTOMOTIVE PRODUCTS CORPORATION, A CORPORATION OF DELAWARE.

ELECTRIC SWITCH.

Application filed October 29, 1925. Serial No. 65,645.

My invention relates to manually operated electric switches in which, after the handle or operating member has been moved up to a certain point, and before the movable contact of the switch has moved away from the stationary contact point with which it may be in engagement, an automatic mechanism rapidly throws the arm to another position which may be a position in which the movable contact point is out of engagement with said stationary contact point, or it may be into engagement with the second stationary contact point, whereby the making and breaking of the circuit is substantially instantaneous. Such electric switches are employed for a variety of uses but my improved snap switch is particularly adapted for the ignition circuits of automobiles and especially those wherein the ignition circuit may be supplied at will with current from one of two sources, namely, (1) from a storage battery or (2) from a generator or magneto.

One of the objects of my invention is to provide a construction wherein the snap of the movable contact arm from the battery contact point to the magneto contact point or vice versa is so rapid that a supply of current to the ignition system is practically uninterrupted or is interrupted for so short a time that the production of sparks at the spark plugs is not interrupted and the motor cannot be stalled in changing the circuit from one source of supply to the other.

A further object of my invention is to provide a snap switch which is comparatively small in size and is certain in its action and in which the parts are so protected and enclosed that one may not close the switch at the contact points when the switch is open without turning the handle; that is to say, one in which it is practically impossible to insert or drop a wire into the casing thereby closing the circuit through the contact points.

A further object of my invention is to provide a manually operable switch for the ignition circuit of an automobile which is adapted to be placed or located on the dashboard of a car at a point or position where it is convenient for the driver to manipulate the switch and is so constructed that it is practically impossible to accidentally throw the switch.

A further object of my invention is to

provide a snap switch of the character above described which must be grasped by the hand of the operator and turned in order to throw the switch.

A further object of my invention is to provide a snap switch of the character above described which cannot be thrown by accidentally hitting the handle.

Further objects of my invention will appear in the specification and claims below.

Referring to the drawings forming a part of the specification and in which the same reference characters are employed throughout the various views to indicate the same parts,

Fig. 1 is a front elevational view of my improved switch.

Fig. 2 is a rear view of the switch mechanism, the dashboard being broken away to permit a view of the inside of the casing of the switch; in the position shown, the circuit may be considered as closed through the magneto or generator of an ignition system.

Fig. 3 is another rear view of the switch with the parts thrown to close the circuit through the battery.

Fig. 4 is a substantially vertical sectional view on the line 4-4 of Fig. 2.

Fig. 5 is a more or less diagrammatic view of the parts at the time when the automatic switch throwing mechanism is about to operate.

Fig. 6 is a view similar to Fig. 1 of a slightly modified construction wherein the switch is adapted to coact with a steering wheel lock, the switch being arranged to hold the ignition circuit closed either through the battery or the magneto so long as the steering wheel or other locking part of an automobile is unlocked and in which, after the motor has once been started, the circuit cannot be broken until after the lock is locked.

A switch similar to that illustrated in Fig. 6, and combined with a steering wheel lock, forms the subject-matter of my copending application, Serial Number 711,348, filed May 6, 1924.

Upon the front of the dashboard 1 is mounted the switch casing 2. Preferably, the casing 2 is held to the dashboard by screws 3-3 passing through suitable holes 4-4 through the casing and provided on the rear side of the dashboard with nuts 5-5. A sheet, 6, of insulating material is preferably

interposed between the back of the casing 2 and the front of the dashboard 1, particularly when the dashboard is of metal or is of wood covered with a facing 7 of metal, 5 through which the ignition circuit might be closed if some of the metallic operating parts of the switch enclosed within the casing were to work loose and contact with such metal of the dashboard. When the dashboard 10 is entirely of wood, this sheet, 6, of insulating material might be omitted.

The switch casing 2 is preferably a rectangular piece of pressed or molded insulating material, such as bakelite, and is provided with a circular recess or depression 8 in the rear face thereof, forming therein the chamber 8 in which is housed the contact points and switch mechanism. Embedded in the material of the casing 2 and 15 preferably in the bottom of the depression and near the lower edge of said casing, are two insulated stationary contact pieces or points 9 and 10, preferably alike and extending substantially through the vertical wall 20 of the casing with the inner faces respectively flush with the bottom of the chamber 8. On their outer ends said stationary contact points 9 and 10 are preferably provided with binding screws 11 and 12 respectively for 25 the attachment thereto of the wire 13 which may lead to the magneto and the wire 14 which may lead to the storage battery. Preferably the outer surfaces of the front face and of the bottom edge of the casing 2 30 are provided with grooved channels or depressions 15, 16, substantially semicircular in cross-section at the bottoms thereof and in which the insulated wires 13 and 14 are respectively seated or fitted so that the top or 35 outer surface of the said wires or conductors are just below the surrounding plane surfaces of the casing.

At the center of the chamber or depression 8 is a metal stud 17 extending from the bottom of the depression to the outside of the casing and this stud 17 is provided on its front end with a binding screw 18 for the attachment thereto of a conductor or wire 19 running to the induction coils (not shown) 40 of the ignition system. This wire 19 is also preferably fitted in a groove or channel 20 extending parallel to the channels 15 and 16. The inner end of the stud 17 projects above the bottom surfaces of the depression 8 and 45 forms a journal or shaft on which is pivotally mounted the switch arm 21 and the cam member 22, the said arm and cam being retained on the stud 17 between the head of the screw 23 threaded into the inner end 50 of the stud 17 and a shoulder 24 provided on the stud. A light washer 25 may be interposed between the switch arm 21 and the shoulder 24. Both the switch arm and the cam member are free to turn on the 55 stud 17. They are capable of a slight in-

dependent movement relative to each other about said stud 17 as a pivot but such motion is limited by a pin 26 projecting from the rear surface of the arm 21 and entering a hole or opening 27 through the cam member 22, said opening 27 being of a little larger diameter than the diameter of the pin 26.

The upper side of the cam member 22 is provided with a few gear teeth 28 which are adapted to mesh with coacting gear teeth 29 in the perimeter of a disc 30 rigidly mounted on the inner end of a shaft 31 mounted to rotate in a bushing or bearing 32 fixedly molded into and passing through the front wall of a switch casing 2. The outer end of the shaft 31 is provided with a knob or handle 33, secured thereto by a transverse pin 34 passing through the shaft and through the hub of the knob 33. The knob or handle 33 may be provided with an index or pointer 35 by the position of which with respect to suitable indications 36, 37, such as "MAG" and "BAT" the operator may throw the switch to obtain his power for the ignition system from either source of electricity.

At opposite ends of the gear teeth 28 on the cam member 22 are stop projections or shoulders 38 and 39 respectively adapted to abut against the cylindrical surface of the disc 30 to limit the throw of the disc and cam.

The outer end of the switch arm 21 is preferably provided with a metallic contact point 40 having a smooth undersurface adapted to freely slide over the smooth surfaces 9' and 10' of the stationary contact points 9 and 10 respectively and over the smooth inner flat bottom surface of the chamber 8 between said stationary contact points 9 and 10. Because the insulating material of which the casing 2 may be composed may be somewhat softer than metal and may therefore in time become abraded by the sliding of the contact 40 thereover, I prefer to embed in the casing substantially midway between the contact points 9 and 10 a metallic pin or stud 41, the end of which is flush with the bottom of the depression or chamber 8. The contact point 21 will thus slide over and wear the metallic contact points 9 and 10 and the pin 41, and the material between the contact points 9 and 10 will not be worn away. It will be evident that the wearing away of the insulating material between the contact points 9 and 10 would in time produce shoulders at the adjacent edges of the stationary contacts 9 and 10, and such shoulders might interfere with the smooth movement of the contact point 40 thereover.

The arm 21 is preferably a resilient arm arranged to press the contact point 40 firmly against the metallic surfaces above referred to, and therefore, to hold this contact point

40 securely at the end of the arm 21, it is merely necessary to provide the rear side of the contact 40 with a small stud 42 fitting into a cylindrical hole 43 at the end of the arm 21. The resiliency of the arm 21 pressing against the contact point 40 will prevent its separation from the arm 21 during the ordinary manipulation of the switch. Should the contact point 41 become worn and need should be found to replace the same, it is a comparatively simple matter to spring the arm 21 away from the bottom of the depression 8, separate the contact point 40 therefrom and replace it with a new contact point.

The cam member 22 is also provided with a cam projection 44 which is somewhat heart-shaped or triangular and the high point of this cam is preferably a sharp edge 20 45 extending transverse to the face of the cam and parallel to the axis thereof. On both sides of this sharp edge 45, the cam projection 40 preferably curves downwardly away from the sharp edge 45 toward the stud or shaft 17.

Cooperating with the said projection 44 on the cam 22 is a cam follower 46 which is operative, at the proper time, to snap the switch arm 21 from one contact point 9 to the other point 10 and vice versa and this member may consist of a lever pivoted at one end on a pivot screw or stud 47. The free end of said pivoted member 46 is preferably provided with a stud or pin 48 to which one end of a spiral spring 49 is attached, the other end of said spring being similarly connected to a stud or pin 50 rigidly mounted in the bottom of the recess or chamber 8. The follower member 46 on the side adjacent the cam member 22 is preferably also provided with a projection 51 terminating in a relatively sharp edge 52 and the sides of the projection 51 on each side of the edge 52 are preferably curved downwardly and away from the said edge 52. The edge 52 also extends transverse to the pivoted member 26 parallel to the axis of the cam member 22 and parallel to the sharp edge 45. The sharp edges 45 and 52 on the cam member 22 and follower member 46 are preferably so disposed with respect to each other than when the apex of the projection 44 of the cam is midway between the stationary contact points 9 and 10 or more broadly when the cam member 22 has been moved for one-half of its complete throw, the edge 45 on the cam will be in alinement with the sharp edge 52 on the member 46. It is, of course, impossible for these two sharp edges to remain in this position. The tension of the spring 49 is such that the instant the sharp edge 45 on the cam 22 passes over the sharp edge 52 on the member 46, the spring will immediately advance the cam independently of the han-

dle or knob 33 and snap the arm 21 to the other stationary contact point 10. This critical position of the cam and switch throwing member 46 is illustrated in Fig. 5.

Over the front of the switch casing 2 I 70 preferably provide a plate or cover 53 which fits against the flat face of the switch casing 2 and against the under edge of it over the channels 15, 16 and 20 covering the wires 13, 14 and 18 and protecting them from easy 75 access and from the weather. This plate 53 may be rigidly secured to the casing 2 by screws 54. Preferably the lower inner edge 53' of the plate 53 is spaced from the dashboard 1 by the diameter of the insulated 80 wires 13, 14 and 19 and is rounded downwardly, thus serving to hold the said wires against the dashboard without cutting through the insulation. Said plate 53 may be of metal or may be of insulating material, 85 such as fiber or of metal and lined with insulating material. In the preferred form of my invention, the plate 53 is of metal and between it and the casing 2 I preferably insert a thin sheet 55 of insulating ma- 90

terial so that if by any chance the binding screws 11 and 12 work loose and outwardly so far as to make contact with the cover, the sheet of insulating material will prevent any shortcircuiting of the ignition system, as 95 would occur were the plate or cover 53 to be made of conducting material and without such an inner lining 55 of insulating material. It is for the same purpose that the sheet 6 of insulating material is placed under 100 the switch casing 2 and between it and the dashboard 1, for if the face of the dashboard were a metal sheet, and the heads of the screws 23 and 47 became loose and worked out into contact with such electrically conductive surface, a shortcircuiting of the ignition system would take place.

Having thus described the preferred form of my invention, it will be plain that with the parts constructed and arranged as shown 110 in Fig. 1, the ignition circuit of an automobile would be closed through the magneto wire 13, the stationary contact point 9, the movable contact or switch arm 21, the metallic stud 17, the binding screws 18 115 and the wire 19. In the position shown in Fig. 2 the ignition circuit would be closed through the battery wire 14, stationary contact point 10, the switch arm 21, the stud 17, back to wire 19. 120

To throw the magneto out from the ignition circuit and throw the battery into the ignition circuit, the operator would turn the knob or handle 33 to bring the index 31 from the position shown in Fig. 3 toward the indication "BAT". When the operator has so turned the knob 33 and brought the parts connected thereto up to the position shown in Fig. 5, the movable contact point 40 will still be on the stationary contact point 9, the 130

cam 22 will have completed one-half of its complete throw, and the sharp edge 45 thereof will be substantially coincident with the sharp edge 52 on the member 46. The instant the sharp edge 45 passes the sharp edge 52 on the member 46, the spiral spring 49 will draw the projection on the follower down over the projection 44 of the cam and the cam will be advanced by reason of a substantial backlash which I provide between the teeth 28 on the cam 22 and the teeth 29 on the disc 30. This backlash is made ample to permit the follower or switch throwing member 46 to throw the cam far enough to bring the contact 40 on the end of the arm 21 into electrical engagement with the stationary contact point 10. This motion or throw of the arm 21 is rapid and substantially instantaneous. The space between the contact points 9 and 10 is but a hair's breadth greater than the diameter of the contact 40 on the end of the arm 21 so that while the contact 40 may not be in engagement with both stationary contact points at the same instant,—that is to say,—may not close the ignition circuit through the battery and through the magneto simultaneously, the time that the contact 40 is out of electrical engagement with both stationary contacts is infinitesimal and the ignition circuit is for practical purposes unbroken. An instantaneous break and make of the circuit will not interrupt the regular continuous production of sparks at the spark plugs of the ignition system.

The loose connection between the movable contact or switch arm 21 and the cam 22 is a loose intermeshing or inter-engaging connection and is of such a nature as to cause the switch arm to lag behind the cam as it is being dragged along by the cam in either direction and the space between the pin 26 on the arm and the hole 27 in the cam is so proportioned that the contact point 40 on the arm 20 cannot be manually moved out of engagement with a stationary contact point until the sharp edge 45 on the cam has passed over the sharp edge 52 on the follower or switch throwing member 46.

It is to be understood if the hole were in the arm 21 and the pin on the cam 22 the operation would be substantially the same.

In Fig. 6 is shown a modified construction of my improved switch member particularly adapted and arranged for cooperation with the bolt 56 of a steering wheel lock (not shown). In this construction the switch casing is placed under the bolt 56 and the index finger or pointer 35 of the construction shown in Fig. 4 is extended upwardly to form an arm or handle 35' into the path of motion of which the bolt 56 extends when the steering wheel is unlocked. This type of steering wheel lock and an ignition switch cooperating therewith is fully disclosed in

my copending application, Serial Number 711,348, above referred to.

In the switch shown in Fig. 6, the movement of the movable contact arm or switch arm 21 is not limited merely to a movement from one contact point to another. Whenever the bolt 56 is in the unlocked position and projects into the path of the arm 35, the movement of the switch arm 21 is so limited and confined to a movement from one stationary contact point to the other. But when the steering wheel is locked and the bolt 56 is out of the path of movement of the arm 35', then the contact arm 21 may move by the cam follower further to the right of the magneto stationary contact point 9 to a position shown in Fig. 6 where it is out of contact therewith and the ignition circuit to the battery and to the magneto is broken and no current is supplied to the ignition circuit. To effect its operation, it is merely necessary to provide the cam member 22 and the disc 30 with one or more teeth 28' and 29' respectively and to position the stop lugs 38' and 39' so as to permit of a slightly greater movement of the arm 21 in a clockwise direction (when looked at from the rear of the switch, as in Fig. 10) so that the cam 22 may be moved by the follower 46 to swing the contact 40 out of electrical engagement with the magneto contact point 9.

The operation of the two mechanisms is exactly alike except when the bolt 56 is in a locked position and extends into the path of the arm 35' it acts as an abutment to prevent the further movement of the arm 21 in an anticlockwise direction and the stud projection 39 prevents the movement of the arm 21 in a clockwise direction further than the position shown in Fig. 6 when the cam is locked and the bolt 56 is out of the path of the arm 35'.

While the embodiment illustrated on the drawings has been described with considerable particularity, it is to be expressly understood that the invention is not to be restricted thereto, as the same is capable of receiving a variety of mechanical expressions, some of which will readily suggest themselves to those skilled in the art, while certain parts thereof are capable of use without other parts thereof. Reference is therefore to be had to the claims hereto appended for the definitions of the limits of this invention.

Having thus described my invention, what I claim and desire to protect by Letters Patent of the United States, is:

1. In a switch mechanism the combination of a reciprocable cam, the high portion of which presents an acute angle, a cam follower having a projection presenting an acute angle, yielding means continually pressing said projection against said cam, a movable contact member, a loose connection between said member and said cam whereby

10 said member is dragged by said cam and whereby said member lags slightly behind said cam in its motion in either direction, a reciprocable operating member manually operable to move said cam through substantially one-half of its complete throw or movement and a loose connection between said cam operating member and said cam, whereby when the apex of said high portion of said cam passes over the apex of the said projection on said cam follower, the pressure of said follower on said cam automatically throws the cam, and with it said movable contact member to the limit of their movement.

20 2. In a switch mechanism, the combination of a reciprocatory cam providing a projection terminating in a relatively sharp edge extending transverse to the plane of movement of said cam, a cam follower, yielding means continually pressing said follower against said cam, a movable contact member, a loose connection between said member and said cam, a manually reciprocable cam-operating member operable to move said cam from either end of its path of movement to a point substantially midway of its path of movement and a loose driving connection between said cam-operating member and said cam.

30 3. In a switch mechanism, the combination with two stationary contact points, of a reciprocable cam, the high portion of which terminates in a sharp edge extending transverse to the plane of movement of said cam, a cam follower, yielding means pressing said follower against said cam, said cam and follower being positioned so that when said cam has been moved substantially one-half of its complete reciprocatory movement in one direction the engagement between said cam and said follower will be on the side of said edge and the pressure of said follower on said cam will rapidly advance said cam for the balance of its movement in said direction, a movable contact arm member, a loose connection between said member and said cam whereby said member lags slightly behind said cam when moved thereby, and a manually reciprocable cam-operating member operable to move said cam up to said point where said cam follower begins to advance said cam, there being a substantial backlash between said cam-operating member and said cam.

40 4. In a switch mechanism, the combination of a reciprocable cam pivoted to rotate on a fixed axis and providing a projection at the high point of which is a relatively sharp edge extending parallel to the axis of said cam, a cam follower pivoted on a fixed axis parallel to the axis of said cam and having a projection also terminating in a sharp edge extending parallel to the sharp edge of said cam, yielding means continually holding said

50 cam follower pressed against said cam, a movable contact arm pivoted on the axis of said cam, a loose connection between said arm and said cam, a manually reciprocable cam-operating member, a loose connection between said cam-operating member and said cam, and a stationary contact point at one end of the path of movement of said arm, said cam and follower being so positioned with respect to each other and to said contact point that when the edge of said cam is coincident with the edge on said projection of said follower, said arm is still in engagement with said contact point.

55 5. In a switch mechanism the combination with two stationary contact points, of a reciprocable cam, the high point of which terminates in a sharp edge extending transverse to the plane of the movement of said cam, a cam follower having a projection engaging said cam and also terminating in a sharp edge extending parallel to the said edge on said cam, said cam and follower being positioned so that when the cam has been moved to a position substantially midway between the limits of its reciprocatory movement, said edges are coincident, yielding means pressing said follower against said cam, a movable contact member, a loose connection between said contact member and said cam whereby said member is dragged by said cam from one to the other of said stationary contact points, a manually reciprocable cam-operating member operable to move said cam up to said position where said edges are coincident, and a loose connection between said cam-operating member and said cam.

60 6. In a switch operating mechanism, the combination with two stationary contact points, of a cam pivoted to reciprocate on a fixed axis and having a high portion terminating in a sharp edge extending parallel to said axis, a cam follower also mounted on a fixed axis parallel to the axis of said cam and having a projection terminating in a sharp edge and parallel to the sharp edge of said cam, yielding means continually pressing the projection on said cam follower against said cam, a movable contact arm pivoted on the axis of said cam and loosely connected to said cam whereby said arm is moved by said cam but lags a little behind it in its movement in either direction, a manually reciprocable cam-operating member also pivoted to rotate on an axis parallel to the axis of said cam, said cam and said cam-operating member being provided with intermeshing teeth having a substantial backlash between them, said edges on said cam and follower being so positioned with respect to each other that the edge on said cam will pass over the sharp edge on said cam follower before said arm leaves the stationary contact point with which it is in contact.

7. In a switch mechanism, the combination of a reciprocatory cam providing a projection terminating in a relatively sharp edge extending transverse to the plane of movement of said cam, a cam follower, yielding means continually pressing said follower against said cam, a movable contact member, a loose intermeshing connection between said member and said cam, a manually reciprocal cam-operating member operable to move said cam from either end of its path of movement to a point substantially midway of its path of movement and a loose driving connection between said cam-operating member and said cam.

8. In a switch mechanism, the combination of a reciprocatory cam providing a projection terminating in a relatively sharp edge extending transverse to the plane of movement of said cam, a cam follower, yielding means continually pressing said follower against said cam, a movable contact member, a loose connection between said member and said cam, a manually reciprocal cam-operating member operable to move said cam from either end of its path of movement to a point substantially midway of its path of movement and loosely intermeshing gearing between said cam-operating member and said cam.

9. In a switch mechanism, the combination of a reciprocatory cam providing a projection terminating in a relatively sharp edge extending transverse to the plane of movement of said cam, a cam follower, yielding means continually pressing said follower against said cam, a movable contact member, a loose intermeshing connection

between said member and said cam, a manually reciprocal cam-operating member 40 operable to move said cam from either end of its path of movement to a point substantially midway of its path of movement and loosely intermeshing gearing between said cam-operating member and said cam. 45

10. In a switch mechanism, the combination with two stationary contact points, of a reciprocal cam, the high portion of which terminates in a sharp edge, a cam follower, yielding means pressing said follower against said cam, said cam and follower being positioned so that when said cam has been moved substantially one-half of its complete movement in one direction, the pressure of said follower on said cam will 55 advance said cam for the balance of its movement in said direction, a movable contact arm, movable back and forth from one of said stationary contact points to the other, a loose connection between said movable contact arm and said cam, whereby said movable contact arm lags slightly behind said cam when moved by said cam, a manually reciprocal cam operating member, operable to move said cam up to a point 60 where said cam follower begins to advance said cam, and a loose connection between said cam and said cam operating member, the distance between said stationary contact points being slightly greater than the width 65 of that portion of the movable contact arm in engagement with said stationary contact points.

In testimony whereof, I have hereunto set my hand this 26th day of October, 1925.

FREDERICK HENKE.
